UNITED STATES PATENT OFFICE.

FRANK L. O. WADSWORTH, OF PITTSBURGH, PENNSYLVANIA, ASSIGNOR TO SKINNER ENGINE COMPANY, OF ERIE, PENNSYLVANIA, A CORPORATION OF PENNSYLVANIA.

STEAM-ENGINE.

1,348,256.

Specification of Letters Patent.

Patented Aug. 3, 1920.

Application filed December 12, 1918. Serial No. 136,460.

To all whom it may concern.

Be it known that I, FRANK L. O. WADSWORTH, a citizen of the United States, residing at Pittsburgh, in the county of Allegheny and State of Pennsylvania, have invented certain new and useful Improvements in Steam-Engines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to steam engines, and has for its object a mode of procedure and an arrangement of mechanism whereby initial condensation within the cylinder will be substantially reduced.

I accomplish this object by providing means, controlled by some moving part of the engine, adapted to convey a portion of the supply of working steam into the hollow engine piston, and therefrom back into the working steam supply, before it has been admitted into the engine cylinder, whereby the end walls of the hollow piston may be raised to and maintained at any desired temperature.

The terms "working steam" and "motor steam" as used in this specification are synonymous, being used to denote steam flowing from a steam generator to the valve controlled inlet ports of the engine and thence to the cylinder to impart motion to the piston of the engine, in contra-distinction to jacket steam.

This invention is applicable to all reciprocating steam engines; therefore while the invention is illustrated in the accompanying drawings as applied to uni-directional flow engines it must not be construed as limited to use with that type of engine.

The features of my invention are herein-after more fully described and pointed out and are illustrated in the accompanying drawings in which:-

Figure 1, is a longitudinal vertical section of a portion of an engine cylinder embodying my invention, showing the piston at the end of its rearward stroke.

Fig. 1^a, is a sectional fragmentary view of a modified construction of the piston.

Fig. 2, is a longitudinal vertical section of a portion of an engine cylinder embodying my invention showing the piston at the end of its forward stroke. 55

Fig. 3, is an enlarged view of a portion of the tail rod construction shown in Figs. 1 and 2 partially in section. 60

Fig. 4, is an enlarged modification thereof.

Fig. 5, is a longitudinal vertical section of a portion of an engine cylinder showing another form of mechanism embodying my invention, the piston being at the end of its rearward stroke. 65

Fig. 6, is a like view thereof, showing the piston at the end of its forward stroke. 70

Fig. 7, is a longitudinal vertical section of a portion of an engine cylinder showing another form of mechanism embodying my invention, the piston being at the end of its rearward stroke. 75

Fig. 8, is a like view showing the engine piston at the end of its forward stroke.

Fig. 9, is a longitudinal vertical section of an engine cylinder showing another form of mechanism embodying my invention, the engine piston being at the end of its rearward stroke. 80

Fig. 10, is a like view showing the engine piston at the end of its forward stroke.

Fig. 11, is a vertical central section of one of the cylinder heads showing a modification of Figs. 9 and 10. 85

Fig. 12, is a longitudinal vertical section of an engine cylinder showing another form of mechanism embodying my invention with the engine piston at the end of its rearward stroke. 90

Fig. 13, is a like view thereof showing an engine piston at the end of its forward stroke. 95

Fig. 14, is a transverse section on the line, x-x in Fig. 13.

In these drawings A indicates the engine cylinder having thereon the usual inlet valve seats A' and inlet ports a leading from the valve seats A' to the interior of the cylinder A. A² indicates the hollow cylinder head on the rear end of the cylinder A, into which motor steam from the steam supply of the engine is introduced for the purpose of heating the inner wall a' thereof. A³ indicates the hollow cylinder head on the front end of the cylinder (see Figs. 9, 10, 11, 12 100 to 105

and 13). B indicates the hollow piston, and B' indicates the piston rod secured to the hollow piston B.

In Figs. 1, 2, 3 and 4 a hollow tail rod C extends rearwardly beyond the hollow piston B, through a stuffing box a^2 in the rear head A^2 , the interior thereof communicating with the cavity in the piston B by means of an opening C' from which a piece of tubing C^2 extends downwardly to a pocket 10 b in the wall of the piston B at the lower side thereof. Within the tail rod C is placed a tube D which is of smaller exterior diameter than the interior diameter of the tail rod C, so that there is an annular passage 15 between the tube D and the interior wall of the tail rod C.

The tube D is maintained in spaced relation to the tail rod C by being inserted into a longitudinal opening b' in the piston rod B' and by a valve housing D' secured in the rear end of the tail rod C and on the rear end of the tube D. Within this valve housing D' I place a check valve D² which opens 20 inwardly (see Fig. 3). The tail rod C is provided with a port opening C^3 . Inclosing the tail rod C is a casing E in which there is secured a bushing E' which serves as a bearing and guide for the tail rod C and divides the interior of the casing E, forming 25 therein a chamber e in the rear end thereof, and a chamber e' therein adjacent to the cylinder head A^2 . The chamber e' in the casing E communicates with the interior of the cylinder head A^2 by means of an opening a^3 through the rear wall of said cylinder head. The casing E is provided with a duct 30 e^2 which leads from an opening a^4 in the rear wall of the cylinder head A^2 to a port opening e^3 through the wall of the casing E and bushing E', which port opening is preferably provided with a valve e^4 for controlling the same.

In operation when the piston B is moved 40 forward by steam admitted into the inlet port a to the position thereof shown in Fig. 2, the tail rod C moves forwardly within the casing E and lowers the pressure within the chamber e in said casing until the port opening e^3 is uncovered by the tail rod when 45 steam from the interior of the cylinder head A^2 will flow into the chamber e behind the rear end of the tail rod C, which occurs at the end of the forward stroke of the piston B, when there is little, if any, movement 50 thereof while the engine crank (not shown) passes its center. The quantity of steam which passes through the port e^3 into the chamber e at the end of the forward stroke 55 of the piston B is regulated somewhat by the size of the port e^3 , and also by the speed of the engine; because if the engine is running at full speed the pause of the tail rod at the end of the forward stroke of the piston is of 60 shorter duration than when the engine is 65

running at reduced speed; and in that case the port e^3 will be uncovered momentarily, while the lowering of the pressure in the chamber e by the forward movement of the tail rod C will be the same at any speed of 70 the engine. On the return of the piston B from the position thereof shown in Fig. 2, to that shown in Fig. 1, the steam trapped in the chamber e by the closing of the port opening e^3 will be forced through the valve 75 D^2 in the rear end of the tail rod, and thence through the tube D into the piston B through the opening C^4 , the port opening C^3 in the tail rod being uncovered during a large portion of the rearward travel of the 80 tail rod and communicating with the chamber e' in the casing E so that the continued reciprocation of the piston B and tail rod C will cause a pulsating flow of steam through the valve D^2 , piston B, and back 85 into the cylinder head A^3 .

It will be noted that during the operation of the mechanism above described, when the port opening C^3 in the tail rod C moves rearwardly into the bushing E the 90 flow of steam from the piston cavity through said tail rod is stopped, and that therefore from the time of the closing of said port opening C^3 to the end of the rearward movement of said tail rod into the 95 chamber e, steam within said chamber e is forced through the valve D^2 and tube D into the piston cavity, while there is no means by which it can escape therefrom, thereby increasing the pressure within said 100 cavity during the latter portion of the rearward movement of the hollow piston B. Then when the piston B and tail rod C moves forward the pressure in the chamber e is reduced by reason of the removal therefrom of the cubic volume of that portion of the tail rod which extends rearwardly from the port opening e^3 .

In Fig. 4 I show a modification of the above described mechanism in which the check valve is removed from the end of the tail rod and placed in the steam duct e^2 in the casing E, said duct e^2 being extended to the rear end of the casing E. In this figure, C^5 indicates the tail rod having a tube D^4 which is open, with a bushing d between the tube D^4 and the tail rod C^5 ; and in the duct e^2 of the casing E near the rear end thereof, I place a check valve D^5 to prevent the backward flow of steam through said duct during the rearward movement of the tail-rod C^5 . I also preferably provide a regulating valve e^4 which cooperates with the port opening e^5 to resist the flow of steam through said port opening. By means of this mechanism the steam which flows through the duct e^2 and port e^5 to fill the space in the casing E occupied by the tail-rod C^5 and tube D^4 during the forward movement of the tail-rod, must, during the rearward 120 125 130

movement of the tail-rod, go forward through the tube D⁴ into the piston B, and then backward through the tail-rod outside of the tube D⁴ and out through the port 5 opening C³ in the tail-rod during the movement of the tail-rod from the position thereof shown in Fig. 2, to the position shown in Fig. 1.

It will thus be seen that applicant has 10 provided mechanism in which there is a chamber of reduced pressure during the forward movement of the piston into which steam is admitted at the end of said forward movement, and the passage through

15 which steam is admitted to said chamber is provided with a valve e⁴ by means of which said passageway may be restricted as desired, and that during the rearward movement of the piston the steam therein is compressed sufficiently to force it back into the 20 supply of motor steam in the hollow head A².

The use of heated piston construction is peculiarly advantageous in reducing initial condensation of steam when it first enters 25 the ends of the engine cylinder and comes in contact with the ends of the piston. In order to obtain the maximum advantage it is desirable that the ends of the piston should be maintained at substantially the same temperature as that of the entering steam. It 30 is not always possible to do this because the central portions of the piston will be cooled somewhat below the temperature of the heated ends by reason of the contact between the periphery of the piston and the 35 central portion of the cylinder walls. This cooling effect can, however, be minimized by insulating the central portion of the piston from the end portions and also by insulating 40 the central portion of the piston from the portions of the cylinder wall in the neighborhood of the exhaust ports. One of the simplest means of securing the latter result is to reduce the diameter of the central part 45 of the piston between the piston rings in the manner shown in Figs. 1 and 2. This reduction in diameter leaves a narrow annular space between the piston and the wall of the cylinder, which serves not only to 50 insulate the parts and prevent the direct conduction of heat from the piston to the cylinder in the neighborhood of the exhaust ports, but performs another useful function in the trapping and retaining of a certain 55 amount of moist, low pressure steam that acts as a lubricant to the moving surfaces. The insulation of the piston ends from the central portion of the body of the piston may be effected where desired, by such a 60 construction of piston as that shown in Fig. 1^a, where the central shell l of the piston is formed separately from the ends thereof, which ends are bolted or otherwise secured to the shell l with an interposed 65 gasket of non-conducting material between

the parts. It will be further understood that the advantage of insulating the central portion of the piston from the hot ends thereof and from the cylinder exhaust—such as has been described in the construction 70 shown in Figs. 1 and 2—can be utilized in connection with all of the other constructions disclosed herein, as well as in connection with such other modifications as may be readily devised to embody the principles 75 of my invention.

In Figs. 5 and 6 a hollow tail rod F extends rearwardly from the piston B through a stuffing box a² in the rear cylinder head A², and is provided with a port opening f adjacent to the rear end thereof. From the interior of the hollow piston B an opening b² communicates with the interior of the hollow tail rod F; within the tail rod F there is a hollow extension F' on the piston rod B', which communicates with the interior of the piston B through the duct b³. This hollow extension F' of the piston rod B' is preferably of a length equal to the travel of the piston B. 80

Against the rear wall of the cylinder head A² I place a casing F² which covers the tail rod F as shown in Fig. 5; and secured in the rear end of the casing F² there is a tube G which extends forwardly toward the inner end of the cavity in the piston rod extension F', the bore g of the tube G communicating with the duct b³ when the piston is at the end of its backward stroke, as shown in Fig. 5; the tube G is also provided with a 100 port opening g' adjacent to its closed rear end. 90

Within the casing F² I secure a bushing F³ adapted to form a bearing and guide for the tail rod F and prevent the escape of 105 steam around said tail rod. In the upper portion of the casing F² there is a duct f' which communicates with the interior of the cylinder head A² through an opening a⁴ in the rear wall thereof, and with a port opening f² in the bushing F³. On the tube G I secure a piston G' which fits the interior surface of the tail rod F, and is located therein just back of the port opening f² in the bushing F³; and said casing F² is 115 provided with a duct f³ which communicates with the interior thereof at a point to the rear of the bushing F³, and with the interior of the cylinder head A² through an opening a³ in the rear wall thereof. 120

In the operation of the mechanism shown in Figs. 5 and 6 steam is admitted into the cylinder head A² to heat the inner wall a' thereof and to the inlet port a through the valve seats A' to move the piston B forward, 125 and as it moves forward communication between the tube G and the duct b³ in the piston B is cut off, which prevents any backward flow of steam from the casing F² through the tube G into the piston B and 130

the tube G and the piston G' thereon operate to reduce the pressure within the tail rod F and piston B, and the piston rod extension F', during the forward movement of said parts; said reduction of pressure within said parts continuing until the port f in the wall of the hollow tail rod F passes the piston G' and comes into coincidence with the port opening in the bushing F³ during the short pause of said piston B at the end of its forward stroke, thus reducing the pressure in a series of communicating chambers consisting of the hollow tail rod, hollow piston, and hollow piston rod extension during the forward movement of said parts, into which steam is admitted from the cylinder head A² at the end of the forward travel of the hollow piston B.

The quantity of steam which rushes into the hollow tail rod and hollow piston during the coincidence of the port f and port f², is regulated somewhat by the size of said ports and also by the speed of the engine; because if the engine is running at high speed the period of coincidence of said ports is of shorter duration than when the engine is running at reduced speed, while the piston G' and tube G will exhaust the same cubic content from the piston B and tail rod F at all speeds during each reciprocation thereof.

On the return movement of the engine piston B to the position thereof shown in Fig. 5, the tube G and the piston G' forces the steam trapped by the closing of the port f² from the tail rod F and piston rod extension F' into the cavity of the piston B wherein it is compressed during the rearward movement of the piston B until the duct b³ in the piston B coincides with the opening in the tube G, which relieves the compression by permitting the compressed steam to escape from the piston to the rear end of the tube G and thence into the casing F² from which it can flow through the duct f³ into the cylinder head A².

It will therefore be seen that a limited quantity of motor steam is thus introduced into a series of communicating chambers including the piston B after the pressure therein has been reduced, and that as the speed of the engine increases, the amount of steam introduced thereinto at each forward movement thereof, is reduced by reason of the lessening of the period of time in which the port f in the tail rod and port f² in the bushing F³ are in coincidence; also that said steam is compressed within said series of chambers, and the pressure thereof has been raised sufficiently to cause a flow back into the supply of motor steam within the cylinder head.

In Figs. 7 and 8 the piston rod B' is provided with an extension H which extends rearwardly through a stuffing box a² in the rear cylinder head A² and has therein two

ducts H' and H²; the duct H' extending from the rear end of the piston rod extension forwardly to a point adjacent to the inner surface of the front end wall of the engine piston B, where a lateral opening h¹ communicates with the interior of the engine piston B; and the rear end of said duct H' is provided with a port opening h¹ in the wall of the piston rod extension. The other duct H² extends forwardly from the rear end of the piston rod extension H to a point adjacent to the inner face of the rear wall of the engine piston B where a lateral opening h² communicates through a short tube h³ with the interior of the engine piston B; said duct H² being provided with a port opening h⁴ through the wall of said piston rod extension adjacent to the rear end thereof. The rear ends of said ducts H' and H² are closed by means of screw plugs z. 85

Secured against the rear face of the cylinder head A² is a casing I which incloses the piston rod extension H and in which is secured a bushing I' which operates as a bearing of the piston rod extension H; the casing I is provided with a duct i which communicates with the interior of the cylinder head A and with the port opening h⁵ in the bushing I'. At the underside of the casing I there is a duct H³ extending from the rear end thereof to, and communicating with an opening a³ in the cylinder head A². To the rear end of the casing I is secured a valve chamber J and a valve J' opening thereinto, from which valve chamber a passage J² leads into the duct H³. The duct i is provided with a regulating valve K adapted to restrict the passage of steam therethrough.

In operation steam is admitted to the hollow head A² and inlet port a, and as the piston B moves forward, the piston rod extension H leaves a space in the casing I in which the pressure is reduced, and when the port opening H' in the side of the piston rod extension H coincides with the port opening h⁵, and the port opening h⁴ in the piston rod extension H comes over the slot h⁶ in the bushing I as shown in Fig. 8, said reduced pressure is communicated through the duct H² to the cavity in the piston B, and the ports h¹ and h⁵ being coincident, steam from the duct i rushes through the duct H' into the piston B, and the continued reciprocation of said ports draws the steam from the hollow piston B through the duct H² into the interior of the casing I, from where it is compressed through the valve J' and duct H³ into the cylinder head, while fresh steam is admitted into the duct H' during the period of coincidence of the ports h¹ and h⁵ at the end of each forward stroke of the piston B. In other words the pressure in the cavity of the piston B is sufficiently reduced by reason of the forward movement of the tail 130

rod extension within the casing I, to permit steam to flow thereinto when the ports h' and h^5 coincide, and the port h^4 and slot h^6 coincide at the end of the forward stroke of the piston B.

- As the ports h' and h^5 , and the port h^4 and slot h^6 only coincide at the end of the forward stroke of the piston, during the pause thereof, while the engine crank is crossing its dead center, it will be obvious that as the speed of the engine increases, the pauses at the ends of the strokes of the piston will be lessened in duration; while the capacity of the tail rod and casing I to cause an indrawing of steam into the piston, while remaining the same for each forward and backward movement of the piston, will be greatly increased by the increased frequency of the piston strokes; the length of the slot h^6 permitting a longer period of time for the reduced pressure in the chamber I to exhaust steam from the piston B.

In Figs. 9 and 10 I show another form of mechanism which embodies my invention, in which a sleeve L is secured in the front cylinder head A^3 which extends rearwardly into the cylinder, and a short distance into the piston B, when said piston is at the rear end of its stroke. In this case the piston is provided with semi-spherical end walls, and the front and rear cylinder heads A^2 and A^3 have their inner walls a' concaved to fit the contour of said piston end walls. In this manner the piston can be lengthened for the purpose of embodying the form of mechanism shown in Figs. 9 and 10 without shortening the length of the piston stroke.

- The piston B is provided with a longitudinal cylindrical chamber L' , into which the sleeve L projects, thus leaving an annular space or chamber l around the piston rod B'. Within the cylinder head A^3 there is a port opening l' through the wall of the sleeve L; and I also provide a port opening l^2 in the wall of the sleeve L inside of the cylinder adjacent to the inner wall of the cylinder head A^3 ; and in spaced relation to the rear of the port opening l^2 there is another port opening l^3 in the wall of the sleeve L.

Within the piston B I provide a port opening L^2 in the wall of the cylinder chamber L' , and another port opening L^3 spaced to the rear thereof, which leads into a duct L^4 extending to the opposite end of the piston B where it turns downward toward the lower wall thereof. The piston rod B' is provided on its upper side with a longitudinal groove B^2 from its rear end forward far enough to communicate with the port opening l' in the sleeve L when the piston is at the end of its forward stroke, as shown in Fig. 10; on the opposite side of the piston

rod B' there is a short groove or slot B^3 of a length sufficient to bridge the port openings l^2 and l^3 in the sleeve L when the piston is at the end of its forward stroke, as shown in Fig. 10.

70

In operation when steam is admitted to the cylinder head A^3 and to the cylinder A, and the piston B moves forward to the end of its stroke, as shown in Fig. 10, the contents of the annular chamber l will be forced through the groove B^2 in the piston rod and the port opening l' , into the head A^3 , and the steam trapped and compressed in the forward end of the cylinder A, (or fresh steam admitted to move the piston B backward)—will flow into the port l^2 through the slot B^3 , port l^3 and port L^2 into the cavity of the piston B. On the completion of the rearward stroke (see Fig. 9) the sleeve L having reduced the pressure in the chamber l uncovers the port openings L^3 , and the steam within the cavity of the piston B will flow through the duct L^4 into the chamber l. On the forward movement of the piston the port L^3 will be closed by the sleeve L and steam thus trapped in the chamber l will be compressed and forced back through the slot B^2 and port l' into the forward cylinder head A^3 . When the piston B is at the forward end of its stroke all of said port openings are open to the passage of steam therethrough, but, because the port opening L^3 is closed at that time there is no direct circulation of steam through the piston, but the same is compressed in the piston cavity.

95

The time of coincidence of the ports l^2 and l^3 in the sleeve L with the slot B^3 in the piston rod, and the port L^2 in the piston during the pause of the piston at the end of its forward stroke being controlled by the speed of the engine, it is obvious that the amount of steam which will be admitted to the interior of the piston B at the end of each forward stroke will be reduced as the speed of the engine increases, while the capacity of the sleeve L acting in the cylinder L' to exhaust the steam from the interior of the piston, is not reduced.

105

In Fig. 11, I show a modification in which the short lower slot B^3 is extended forward into the front cylinder head A^3 where it communicates with the interior thereof through a valve controlled opening l^4 , so that instead of the piston B receiving steam from the compression space of the cylinder A, it receives steam from the head A^3 . In this case I provide a valve K by means of which the flow of steam through the opening l^4 may be restricted as desired.

115

In both of the last described forms of mechanism, high pressure steam from the cylinder A, or the cylinder head A^3 will flow through the ports l^2 and l^3 , and L^2 , into the interior of the piston B at the end

120

125

130

of the forward stroke of the piston, and when the piston B returns to its rearmost position, as shown in Fig. 9, the pressure in the chamber l having been reduced, the 5 steam within the piston will flow through the duct L^4 into the annular chamber l , wherein it is compressed and returns into the cylinder head A^3 when the piston B reaches the end of its forward stroke.

10 In Figs. 12 and 13 the rear portion of the piston rod B' is hollow and into the hollow end of the piston rod B' a stationary rod M extends, which is secured in a bushing plug M' secured in the rear head A^2 . This rod 15 M has a longitudinal opening M^2 therethrough, terminating, at its rear end, in a valve seat upon which a valve M^3 is seated. This valve is held in position by means of a stem m slidably mounted in an opening in 20 the bushing plug M' , said opening being provided with a small lateral opening m' , through which steam from the cylinder head A^2 may enter behind the valve stem m to maintain the valve M^3 closed.

25 There is provided an opening b^4 from the chamber B^4 in the piston rod B' into the interior of the piston B. The piston B is provided with a port opening N in the wall thereof, which, when the piston B is at the 30 end of its forward stroke coincides with a port N' in the cylinder A communicating with the inlet valve seats A' at the front end of the cylinder. The port N' is provided with a regulating valve N^2 (see Fig. 35 14) adapted to restrict the passage of steam therethrough.

In operation steam is admitted to the cylinder heads A^2 and A^3 and to the rear inlet port a , and the piston B moves to the 40 end of its forward stroke, the rod M acting to reduce the pressure in the hollow piston rod B' during the forward movement of the piston, until the port N in the piston coincides with the port N' in the cylinder A; 45 and the port b^4 in the wall of the piston rod is uncovered by the rod M , when the reduced pressure in the cavity B^4 in the piston rod will be communicated to the cavity in the piston B and steam from the forward 50 valve seat A' will rush into the piston cavity; this entry of steam into the hollow piston taking place during the pause of the piston while the engine crank is passing its dead center, it is obvious that the greater 55 the speed of the engine, the shorter will be the interval of time that the ports N and N' will be in coincidence to permit the passage of steam therethrough, and on the return of the piston B to the position shown in 60 Fig. 12, the steam trapped in the cavity B^4 in the piston rod will be forced backward through the longitudinal opening M^2 in the rod M , and past the valve M^3 into the supply of motor steam in the head A^2 . Likewise, 65 as the speed of the engine increases, the

quantity of steam entering the piston cavity is necessarily decreased, while the exhausting capacity of the rod M remains the same at each reciprocation of the engine piston. The quantity of steam which will flow 70 through the ports N and N' may be restricted by the use of the valve N^2 .

In the use of steam heated pistons in steam engines it has been found that as the speed of the engine increases, the flow of 75 hot steam through the piston is increased with the result that the piston becomes too hot and is detrimental to the operation of the engine, because of the deleterious effect on packing and lubricants. This difficulty 80 is entirely overcome by my invention for the reason that as the steam is only admitted to the circulating mechanism at the end of the piston stroke while the engine crank is passing its dead center by means of coinciding port openings, the flow of steam is but momentary, the piston having to make a complete reciprocation between the admissions of steam. The steam in all of the constructions herein shown and described, 85 entering a chamber of reduced pressure, is compressed sufficiently to cause it to flow back into the supply of motor steam, but as the engine speed increases and the admission of steam grows consequently less in 90 quantity, it may be possible that steam from the engine piston may not be ejected therefrom at each backward movement of the piston, as it may require several backward strokes of the piston to build up sufficient 95 pressure therein to overcome the pressure in the steam supply. This admission of steam may be restricted by valves as hereinbefore described, if it is found that the piston becomes overheated.

105 From the foregoing description of the construction and operation of the several forms of mechanism adapted to embody my invention, it will be obvious to those skilled in the art, that I am enabled, thereby, to 110 heat the end walls of an engine piston as may be desired, by introducing a portion of the engine's supply of steam into the engine piston and conveying it back into said supply of steam without substantial waste 115 of steam.

Having thus fully shown and described suitable mechanism for embodying my invention so that the same may be utilized by others, I do not desire to be limited to the 120 exact mechanism shown and described, as many alterations and modifications can be made therein without departing from the scope of my invention. Therefore what I claim as new and desire to secure by Let- 125 ters Patent is:—

1. The combination in a steam engine, of a hollow piston, circulating mechanism including a cylinder and piston in communication with said hollow piston adapted to 130

receive steam and cause it to circulate through said hollow piston, said cylinder having a steam inlet port adapted to be uncovered by the piston therein at the end of 5 one stroke of the engine piston to permit steam to flow into said cylinder; means to regulate the flow of steam through said inlet port during the time it is uncovered; and means to convey steam away from said 10 circulating mechanism, substantially as set forth.

2. The combination in a steam engine of a hollow piston, circulating mechanism including a cylinder secured on the head of 15 the engine cylinder, and a hollow tail-rod extending rearwardly from said hollow piston, said cylinder and hollow-tail-rod being in communication with said hollow piston and adapted to receive steam and cause it 20 to circulate through said hollow piston; said cylinder having a steam inlet port adapted to be uncovered by the hollow tail-rod at the end of one stroke of the hollow piston to permit steam to flow into said cylinder, and means to convey steam away 25 from said circulating mechanism, substantially as set forth.

3. The combination in a steam engine of a hollow piston, steam circulating mechanism 30 including a tail-rod casing having a steam inlet port, a hollow tail-rod extending from the hollow piston into said casing and adapted to control said steam inlet port, said hollow tail-rod being in communication 35 with the cavity in said hollow piston, a concentric tube within said hollow tail-rod also having communication with the cavity in said hollow piston, means to close the rear end of said hollow tail-rod, a check- 40 valve to control the flow of steam within said concentric tube, and means to convey steam away from said circulating mechanism, substantially as set forth.

4. The combination in a steam engine of 45 a hollow piston, circulating mechanism including a cylinder and piston in communication with said hollow piston adapted to receive steam and cause it to circulate therethrough, said cylinder having a steam inlet 50 port adapted to be uncovered by the piston therein at the end of one stroke of the engine piston to permit steam to flow from the supply of engine steam into said cylinder and means to receive steam from said 55 circulating mechanism and convey it back into the supply of engine steam, substantially as set forth.

5. The combination in a steam engine of 60 an engine cylinder, a hollow steam receiving head thereon, a hollow piston in said cylinder, a hollow tail-rod extending from

said piston rearwardly through said cylinder head, the interior of said piston being in communication with the hollow tail-rod, a port opening in the wall of said hollow tail-rod outside of said cylinder head, a tube concentrically arranged within said tail-rod and also being in communication with the interior of said piston, means to close the rear end of said tail-rod around said tube therein, a casing secured on said cylinder head, a duct in said casing communicating with the interior of said cylinder head, a port opening from said duct to the interior of said casing, the opening and closing of said last mentioned port opening being controlled by said tail-rod so that steam is admitted into said casing from said duct at the termination of the forward stroke of the piston, a non-return valve in 80 the rear end of said tail-rod to insure a circulation of steam from the rear end of said casing through said concentric tube and piston and out through the port opening in said tail-rod, substantially as described. 85

6. The combination in a steam engine of a cylinder, a hollow steam receiving cylinder head thereon, a hollow piston in said cylinder, a hollow tail-rod extending rearwardly through said cylinder head and having a port opening in the wall thereof outside of said cylinder head, the piston cavity being in communication with the bore of said tail-rod, a tube concentrically arranged 90 within said tail-rod being also in communication with the cavity in said piston, means to close the space between the rear ends of said tail-rod and said tube, a non-return valve controlling the entrance of steam into 95 said tube, a casing secured on said cylinder head and inclosing said tail-rod, a bushing arranged in the intermediate portion of said casing around said tail-rod, which bushing divides the interior of said casing 100 into front and rear chambers, the front chamber being in communication with the interior of said cylinder head, a port opening in said bushing, a duct in said casing communicating with the interior of said cylinder head and with the port opening in 105 said bushing, the opening and closing of the port openings in said bushing and said tail-rod being controlled by said tail-rod and said bushing, substantially as described. 110 115

In testimony whereof I affix my signature in presence of two witnesses.

FRANK L. O. WADSWORTH.
